UNITED STATES PATENT OFFICE.

EDWARD EDSEN, OF MILWAUKEE, WISCONSIN.

HEATING SYSTEM.

1,345,149.

Specification of Letters Patent. Patented June 29, 1920.

Application filed February 4, 1918, Serial No. 215,315. Renewed May 13, 1920. Serial No. 381,194.

To all whom it may concern:

Be it known that I, EDWARD EDSEN, a citizen of the United States of America, residing at Milwaukee, in the county of Milwaukee and State of Wisconsin, have invented certain new and useful Improvements in Heating Systems, of which the following is a specification, reference being had thereto in the accompanying drawing.

10 The invention relates to a heating system, and has for its object the provision of a system in which the return water from the radiators is reheated and introduced into the upper portion or steam space of the 15 boiler so as to merely return to the radiators.

It is an object of the invention to provide a heating system which is distinguished by its rapid circulation upon starting of the furnace.

20 A further object is to increase the heating effect without the employment of additional fuel.

With these and other objects in view, the invention consists of the parts hereinafter 25 described and particularly pointed out in the appended claim and illustrated in the annexed drawing, in which—

The figure illustrates a sectional elevation in perspective of a building in which the 30 heating system constructed in accordance with my invention has been applied.

Referring to the drawing, 1 designates a furnace which in the given instance may be utilized for hot water or steam heating. The 35 furnace comprises an outer casing 2, which may be made of galvanized iron or any other preferred or suitable material, and an inner shell 3, spaced therefrom to provide a water chamber in which the water to be heated is stored. The furnace 1 is in communication with a header 4, arranged thereabove and equipped with a riser 5, which is connected by a fitting 6 to a horizontal pipe 7, connected to the various heating elements, 40 such as radiators 8, in the well known manner by the interposition of fittings and valves, the return side of the radiators 8 communicating with the return pipes 9.

The pipes 9 and 10 are connected to the 50 return side of the radiators. At its lower end the pipe 9 is connected to a pipe 11, equipped with a check valve 12 and with a T-fitting 13, whence two pipes 14, 15 lead respectively to a header 16, communicating 55 with the water chamber of the furnace, and to a pipe coil 17, provided in the fire cham-

ber of the furnace, for a purpose presently to be described. The pipe coil 17 is clearly indicated in the drawing and comprises a plurality of convolutions which conform to 60 the contour of the inner wall of the furnace and are supported thereon. This pipe coil is arranged in proximity to the grate of the furnace and above the same, so as to be exposed to intensive heat, without, however, 65 preventing manipulation of the grate for the purpose of cleaning the same and without interfering with the escape of the products of combustion. The other end 18 of the pipe coil leads, by means of a pipe 19, to 70 the header 4 of the furnace, there being a check valve 20 interposed to prevent back flow of the fluid.

The function and utility of the improved heating system are thought to be obvious. 75 Steam generated in the upper portion of the furnace in the water chamber escapes through the pipe 5, and is conducted into the various radiators 8, where, by reason of the prevailing low temperature, the steam condenses. The condensed water returns through the pipes 9 and 10 and flows through the pipe 15, constituting a bleeder, 80 into the pipe coil, where, owing to the intense heat, the water is evaporated and the steam thus formed escapes through the pipes 18 and 19 and past the check valve 20 into 85 the top portion of the water chamber.

From the foregoing it is obvious that due to the rapid conversion of the return water 90 into steam an accelerated circulation of the steam is obtained, thereby insuring a greater efficiency of the heating system without necessitating increased use of fuel or other expenditures with the exception of installation 95 of the pipe coil and its associated parts.

A part of the return water is conducted to the pipe 14, into the lower portion of the water chamber, and thus takes its natural course.

The drawing and specification set forth an embodiment of the invention which, however, is merely indicative of the principle of the invention. A great many changes and alterations may be made within a wide range, 105 and therefore I do not limit myself except to the extent set out by my claim.

I claim:

In a combination with a hot water system, a furnace having a water chamber and a 110 fire chamber, headers respectively connected to the bottom and top portion of said water

chamber, a pipe coil arranged within the fire chamber, means for establishing communication between the pipe coil and the top header, a horizontal pipe section positioned in the return pipe of said heating system, said horizontal section positioned on a level higher than the discharge end of the return side of said heating system, and

a bleeder attached to said horizontal section and connected at its opposite end to said pipe coil whereby communication between said pipe coil and the return side of the heating system is established. 10

In testimony whereof I hereunto affix my signature.

EDWARD EDSEN.
